UNITED STATES PATENT OFFICE

ERNEST J. NEWCOMER, OF YORK, PENNSYLVANIA, ASSIGNOR TO THE FLOOROLA CORPORATION, OF YORK, PENNSYLVANIA, A CORPORATION OF DELAWARE

BRUSH HOLDER

Application filed August 17, 1929. Serial No. 386,684.

This invention relates to an improvement in brush holders. It permits of clearance for this inward spring movement of the ring 4.

I claim:

1. The combination with a brush holder having an internally threaded portion, of a brush head having a peripheral groove therein, a plate fixed to the end of the brush head and having the edge thereof bent back in said groove to form a ring, said ring being externally threaded and normally flared outwardly to be compressed upon engagement with the brush holder. 60

2. The combination with a brush holder having an internally threaded portion, of a brush head having a peripheral groove therein, a plate fixed to the end of the brush head and having the edge thereof bent back in said groove to form a ring, said ring being externally threaded and normally flared outwardly to be compressed upon engagement with the brush holder, said ring being disconnected and free from the sides of the brush head. 70

3. The combination with a brush holder having an internally threaded portion, of a brush head, a plate fixed to the end of the brush head and having the edge thereof bent back to form a resilient ring, said ring being externally threaded and adapted to wedgingly engage the brush holder to be compressed upon engagement with the brush holder, said ring being spaced from the periphery of the brush head. 80

In testimony whereof I affix my signature.

ERNEST J. NEWCOMER. 85

In the accompanying drawing:

Fig. 1 is a plan view of the brush holder; Fig. 2 is a sectional view therethrough; and Fig. 3 is a detail sectional view through a portion of the brush.

The numeral 1 indicates the supporting shaft for the brush, which may be driven by any suitable means, preferably by a machine, to which it is connected and geared for rotary movement over the surface to be treated. The shaft 1 is fixed to a supporting plate 2 having a downturned flange 3 on the outer edge thereof, and extending at right angles to the plate, as shown particularly in Fig. 2, which flange is internally screw-threaded.

A brush head 6 is grooved on its outer surface as at 9 and has a plate 5 secured thereto by means of screws 8 or other fastening devices, as shown in Fig. 2. This plate 5 is preferably made of some thin flexible or resilient material. A threaded ring 4 extends downwardly from the outer edge of the plate 5, being formed integral therewith, and is disposed in the grooved portion 9 of the brush head but is free and clear of the brush head except where it is joined to the plate 5. The ring 4 is threaded to receive the threaded flange 3, but as shown in Fig. 3, when disconnected from said flange, the ring 4, being of spring material, is flared to normally be disposed at an obtuse angle to the plate 5. This flare is such that when the supporting ring 4 is screwed into the threaded flange 3, the latter causes the spring metal ring 4 to be forced inward slightly, thus causing a spring locking effect between the brush and the holder, as shown in Fig. 2. The groove 9
